UNITED STATES PATENT OFFICE.

LOUIS EUGÈNE FAVRE, OF CORMORET, SWITZERLAND.

WATCH.

SPECIFICATION forming part of Letters Patent No. 764,934, dated July 12, 1904.

Application filed September 3, 1903. Serial No. 171,775. (No model.)

To all whom it may concern:

Be it known that I, LOUIS EUGÈNE FAVRE, manufacturer, of Cormoret, Switzerland, have invented certain new and useful Improvements 5 in Watches, of which the following is a specification.

This invention has for its object to provide an improved escapement for watches that will operate with great precision for indicating 10 the dead second; and for this purpose the invention consists of a watch-escapement comprising two or more escapement-wheels secured on a shaft with their teeth in alternating series and a corresponding number of 15 notched disks each arranged to engage one of the escapement-wheels and to engage them in alternation; and the invention further comprises a stud driven from the mainspring and having a barrel loose thereon, a spiral spring 20 in the barrel having one end secured to said stud and having its other end bearing on the inner beveled wall of the barrel, a gear on said barrel, and a pinion meshing with said gear and having said disks secured thereon; and 25 the invention further comprises the novel details of construction and arrangement, as hereinafter set forth and then pointed out in the claim.

In the accompanying drawings, Figure 1 is 30 a plan view of my improved watch-movement. Fig. 2 is a detail plan view drawn on a larger scale. Fig. 3 is a side elevation partly in section. Fig. 4 is a plan view of a modification, and Fig. 5 is a plan view of another modification.

Similar letters of reference indicate corresponding parts.

Referring now to Figs. 1, 2, and 3, *a* is the shaft of a pinion similar to the one of the 40 third wheel and gearing, like it, with the second wheel *e*. On the shaft *a* is loosely mounted the hub *b* of a barrel *b*, having a beveled rim, a spiral spring *d*, having one end secured to a nut *c*, fast on the end of the shaft *a*, the 45 spring being coiled inside the barrel *b*, with its outer end frictionally engaging the inner beveled rim of the barrel. The shaft *a*, with its nut *c*, is continuously rotated by the second wheel *e*; but when the barrel *b* is held

from moving by the escapement the spring is 5° put under tension. The toothed periphery of the barrel *b* gears with a pinion *f*, on whose shaft are secured two superposed toothed wheels, with their teeth *f'* and *f''* alternating, as shown in Fig. 3. On the shaft of the usual 55 escapement *h* are two adjacent notched disks *g'* and *g''*, arranged with the notches alternating and which engage the toothed wheels, respectively, in alternation.

The operation is as follows: The shaft *a* is 60 rotated continuously from the mainspring, while the double escapement-teeth *f'* *f''* are alternately engaged with and disengaged from the two disks *g'* and *g''*, which will put the spiral spring *d* first under tension during each 65 rest of the said double wheel, and then the latter will make a rapid movement until the next tooth is engaged. This will produce a corresponding quick movement of the gear *i*, that drives the seconds-hand *i'*, marking the 70 dead seconds.

In the modification shown in Fig. 4 the notched plate *g''* is carried by a separate shaft *g'*, which gears with a supplementary pinion 75 gearing with the third-wheel movement. In this form the combined range of the teeth of these disks make a tooth-range similar to that shown in Fig. 2, the notches engaging the respective teeth *f'* and *f''* in alternation and producing the same effect on the seconds-hand 80 as in the former construction.

In the modification shown in Fig. 5 there are three superposed notched wheels *f'* *f''* *f'''*, with their teeth alternating, and which engage three toothed disks *g'* *g''* *g'''*. 85

Having thus described my invention, I claim as new and desire to secure by Letters Patent—

In a watch-movement, the combination, with a shaft driven from the mainspring, of a barrel loose on said shaft, said barrel having a 90 beveled-edge recess in its upper face, a spiral spring in said recess having one end connected with said shaft and its other end bearing on the inner beveled edge of the recess, a gear-wheel on said barrel, a pinion meshing 95 with said gear-wheel, a gear-wheel meshing with said pinion and arranged on the seconds-hand arbor, a pair of toothed wheels arranged

with alternating teeth and located on the shaft of said pinion, and a pair of superposed disks having notches alternating and engaging the alternately-toothed wheels, said notched disks being secured to the shaft of the usual escape-
5 ment-wheel, substantially as set forth.

In testimony that I claim the foregoing as

my invention I have signed my name in presence of two subscribing witnesses.

LOUIS EUGÈNE FAVRE.
